UNITED STATES PATENT OFFICE

2,357,751

BAND FOR VENETIAN BLINDS

Maud McGrew, Baltimore, Md.

Application October 15, 1943, Serial No. 506,335

4 Claims. (Cl. 160—178)

This invention relates to Venetian blinds and more particularly to a blind which eliminates the conventional ladder type which supports the slats and may be considered as an improvement of the type of Venetian blind shown in my Patent No. 2,251,361, issued August 5, 1941.

One of the main objects of the invention is to provide simple means whereby the bands may be readily removed from or attached to the blind without removing the complete blind from the window frame.

Another object of the present invention is to provide a Venetian blind with a band composed of a plurality of hinge connections of plastic, metal or other suitable material.

Still another object of the invention is to provide a Venetian blind with bands, each comprising a plurality of hinge-connections which will at all times break uniformly and evenly when operating the blind by means of a pull rope.

Yet another object of the invention is to provide a Venetian blind with bands composed of hinge-connections which will uniformly spread, tilt or collapse the slats when operated by the pull rope, thereby permitting all movements, heretofore desired of Venetian blinds.

Another object of the invention is to provide a Venetian blind with bands which are readily cleanable and may be produced with decorative designs and in any desirable color to secure various decorative color schemes.

A further object of the invention is to provide a Venetian blind with bands which may be quickly removed or attached by anyone without the use of tools.

Yet another object of the present invention is to provide a Venetian blind with bands which are durable, extremely attractive and economical to manufacture.

These and other objects, accomplishments and advantages of the invention will appear in the following description considered in connection with the accompanying drawing forming part of this application, in which:

Figure 1 is an end view of a fragmentary portion of a Venetian blind embodying the invention showing the slats and bands and taken on line 1—1 of Figure 3.

Figure 2 illustrates a fragmentary front view on line 2—2 of Figure 1.

Figure 3 is a fragmentary front view of Figure 1 looking in the direction of arrow "A."

Figure 4 is an enlarged perspective view of the upper half of the hinge-connection embodying the invention.

Figure 5 is an enlarged perspective view of the lower half of the hinge-connection embodying my invention.

Figure 6 is an enlarged, fragmentary perspective view of one of the slats as used in my invention, showing the bars which support the hinge-connections and the position of the pull rope.

Figure 7 illustrates the method of disengaging 10 the slat from one of the hinge members of the bands.

Figure 8 is a fragmentary side view showing the blind in a collapsed position.

Reference being had to the drawing in which 15 similar reference numbers denote like parts in the several views.

Referring now to Figures 1 to 6 of the drawing the numeral 10 indicates the usual slats made of wood, metal or plastic, or any other material 20 suitable for the purpose.

Each of said slats 10 is provided, adjacent the ends thereof, with a pair of oppositely spaced cut-out portions 11, preferably in parallel alignment with the edge 12 of the slats 10, as best 25 shown in Figure 6. A bar 13 is inserted and secured to said edge 12 by spot welding or other suitable methods, if slats are made of sheet steel or by inserting, molding or other suitable methods, the bar ends in the edge of the slats if they 30 are made of plastic, but, of course the bars may be eliminated if the slats are made of sufficiently strong material, such as steel, plastic, etc., to provide rectangular or rounded punch-outs thereby retaining a substantially thin portion of the edge 12 of the slat so as to form the bar 13 integrally with said slat on which the hinge-connection 14 of the band 15 may be attached.

The usual pull or operating rope 16 passes through an aperture 17 at each end of the slats 40 preferably positioned centrally between the bars 13 in order to register with the bands 15 so as to make the pull-rope concealed from view when the blind is in assembled condition.

The bands 15, supporting the slats 10, consist 45 of a plurality of uniform hinge-connections 14, each unit composed of an upper hinge-half 18 shown in perspective in Figure 4 and a lower hinge-half 19 shown in perspective in Figure 5. Said upper hinge-half 18 comprises a substantially flat, S-shaped member preferably molded of plastic or other similar substance and is provided at its bottom with a pair of aligned, and spaced apart hinge-knuckles 20 and the upper portion of said upper hinge-half 18 is provided 50 with a pair of spaced apart, tubular, open bear-

ings 21 preferably formed integral with the body 22 of said upper hinge-half 18.

The lower hinge-half 19 of hinge-connection 14 is provided at its top with a central hinge-knuckle 23 wide enough to be freely inserted in alignment and between the spaced apart hinge-knuckles 20 of the upper hinge-half of said hinge-connection 14.

Assembled, said hinge-knuckles 20 and 23 of the upper and lower hinge-halves are in alignment and adapted to receive a headed hinge-pin or pintle 24 which may be riveted over to form a head 25 for a permanent connection.

The lower hinge-half 19 of said hinge-connection is also provided at its lowermost end with an open, elongated, tubular bearing 26 which preferably extends to the full width of said hinge-half, the free ends 27 of which are adapted to be hingedly accommodated in the spaced apart, open tubular bearings 21 of said upper hinge-half 18.

As will be noted, the lower hinge-half 19 shown in Figure 5 is of substantially cruciform shape, the lower central portion 28 of which integrally supports the bearing 26 for the bar 13 of the slats 10. This central portion 28 is provided with an outwardly flared lower end 30 which merges with the upper edge 31 of slot 29 of the bearing 26, as shown.

In order to attach said hinge-connection 14 to bar 13 of the slats 10, the bearing 26 is open or slotted as indicated by the numeral 29 in its full length so as to provide an entrance for said bar 13 when assembling.

The upper hinge-half 18, as it hingedly engages the free ends 27 of the tubular bearing 26, tilts slightly inwardly, due to its design, while the lower hinge-half 19 tilts slightly outwardly, due to the abutment ridge 32 which extends longitudinally between the inner faces 33 of the hinge-knuckles 20 which come in abutment with the flared face 36 of the lower hinge-half 19, thereby determining the angular position of the latter and thus providing a uniform break of the blind in the proper direction when raising, lowering or tilting the same.

In normal vertical position of the blind, the hinges will assume a position as shown in Figure 1, which clearly shows how the bars 13 of the slats 10 are removably held in the bearings 26, this also applies when the blind is in a collapsed condition as shown in Figure 8 or in a tilted condition, not shown.

The aforesaid flared end 30 of the lower hinge-half 19 comes in abutment with the edge 34 of the upper hinge-half 18 when the latter is raised to a position as shown in Figure 7, in full lines, in order to attach or disengage the bar 13 of the slats 10 to or from the band 15.

While the abutting edge 32 (Figure 4) and the flared face 36 (Figure 5) serve to determine the angular position of the hinge-halves, the abutting edge 34 (Figure 4) and the flared lower end 30 (Figure 5) serve a dual purpose and is of great importance, first, to limit the movement of the hinge-halves 19 and 18 in such manner that the slot 29 of the lower hinge-half 19 and the open ends 35 of the tubular bearings 21 come in alignment with each other when abutting, as best shown in Figure 7, in full lines, and therefore adapted to insert or withdrawn the bar 13 of the slats 10; secondly, that the operator would definitely know by touch that both, the slot 29 and the open ends 35 are in alignment, that is, in a position to readily and quickly insert the bar 13

in the bearing 26 or withdraw same if so desired.

After the bands 15 have been attached to the front and rear edges of the slats 10 as previously described, it will be observed that the hinge-connections 14 are slightly inwardly disposed (see Figure 1) towards the opposite edges of the slats so that when the rope 16 is operated to raise, lower or tilt the blind the hinge-connections will always break uniformly inwardly.

A plurality of uniform hinge-connections 14 are assembled in like manner to complete the blind to the desired length and, obviously, the distance between the slats 10 is determined by the length of the hinge-connections which support the slats at the front and rear edges.

A convenient and quick method to apply the bands to the slats is to attach the rear bands to the slats first so that the slats will hang in place after which the slats can be readily attached to the front bands. This process may be reversed when it is desired to detach the bands from the slats by removing the band from the front first and then at the rear.

To insure a pleasing appearance of the Venetian blind, the bands as well as the slats may be of any desired color and the material may be plastic or other suitable material for the hinge-connections should it be desired to shape the same in the form of flowers, bows or other decorative designs.

The slats as well as the bands may be readily cleaned when required and the method of construction of the blind permits of quickly disconnecting the bands from the slats without removing the complete blind from the window frame.

Each band is independent of the other, thus permitting that only one of the bands be removed, leaving the blind intact, this band may be cleaned and again attached to the blind after which the other band is removed and cleaned and reattached to the slats, thus the blind will be cleaned without taking it completely apart.

Of course, the width of the blind regulates the number of bands, ordinarily two bands are sufficient, although should the blind be unusually wide there may be required one or more intermediate bands. The above described bands 15 may apply to slats as shown in my Patent No. 2,251,361.

As is well known, a Venetian blind comprises in general a head piece, a tilting bar, a bottom bar as well as pulleys and other accessories, all commonly in use to raise, lower or tilt a blind and since there is no novelty in these parts assembled they have been eliminated from the description and are therefore not shown in the present drawing.

A blind as described herewith is readily installed and operated and the bands may be removed or the slats replaced without the use of tools.

Having now fully described the invention and explained its advantages, I wish it understood that within the broader scope of my invention, as defined by the appended claims, various modifications and adaptations may be made without departing from the spirit of the invention.

I claim:

1. In a Venetian blind of the character described, a series of parallel slats each provided with longitudinal bars within the limits of the lateral edges of the slats; bands supporting said slats, comprising a series of hingedly connected portions, each portion composed of an upper hinge-half and a lower hinge-half; the lower

hinge-halves, each adapted to pivot about one of said longitudinal bars of said slats, each upper hinge-half adapted to cooperate with the lower hinge-half next above to retain the associated bar in position.

2. In a Venetian blind of the character described, a series of parallel slats each provided with longitudinal bars within the limits of the lateral edges of the slats and substantial integral therewith; along the edges thereof, bands supporting said slats, comprising a series of hingedly connected portions, each portion composed of an upper hinge-half and a lower hinge-half; horizontally aligned hinge-knuckles for said upper and lower hinge-halves and a pintle therefor to provide an intermediate hinge joint between the slats; the free end of the joined lower hinge-half provided with a centrally supported, tubular bearing adapted to pivotally engage one of said longitudinally disposed bars of said slats; said upper hinge-half provided with means to detachably retain said bar in position in said tubular bearing.

3. In a Venetian blind of the character described, a series of parallel slats each provided with longitudinal bars within the limits of the lateral edges of the slats and substantial integral therewith; bands supporting said slats, comprising a series of hingedly connected portions, each portion composed of an upper hinge-half and a lower hinge-half; horizontally aligned hinge-knuckles for said upper and lower hinge-halves and a pintle therefor to provide an intermediate hinge-joint between the slats; the free

- end of the joined lower hinge-half provided with a centrally supported, tubular bearing adapted to pivotally receive one of said longitudinally disposed bars of said slats; the free end of the joined upper hinge-half next below provided with spaced apart bearing sockets adapted to hingedly embrace the ends of said tubular bearing and means to retain said longitudinal bar of said slats in detachable position in said tubular bearing.
- 5 4. In a Venetian blind of the character described, a series of parallel slats each provided with longitudinal bars within the limits of the lateral edges of the slats and substantial integral therewith; bands supporting said slats comprising a series of hingedly connected portions, each portion composed of an upper hinge-half and a lower hinge-half united thereto to provide an intermediate hinge-joint between said slats; the free end of the joined lower hinge-half having a depending, centrally supported tubular bearing provided with a longitudinal slot extending the entire length thereof; the free end of the joined upper hinge-half provided with a pair of spaced apart bearing sockets, each having a longitudinal opening and adapted to hingedly engage the ends of the tubular bearing of the succeeding lower hinge-half there-above; the longitudinal slot of said tubular bearing sockets, when positioned in parallel alignment with said longitudinal opening, providing a passageway for insertion of one of the bars of said slats into said tubular bearing and means to retain said bar therein.
- 10 15 20 25 30

MAUD McGREW.
